UNITED STATES PATENT OFFICE

HARRY M. ROBERTSON, OF CLEVELAND, OHIO

KILN TRUCK

Application filed April 24, 1929. Serial No. 357,742.

This invention relates to a truck for conveying materials into kilns and supporting them therein during heating and burning, or their heating, burning and cooling. In practice, trucks embodying my invention have been used for supporting and conveying materials through kilns of the continuous type.

One object of the invention is to provide a truck of this character having an improved material supporting or holding member comprising a base and integral webs so proportioned and related that the member may be cast from clay or a clay mixture and then dried and burned without danger of becoming distorted.

Another object of the invention is to provide a kiln truck having a material supporting or holding member formed from a clay mixture having a relatively low co-efficient of expansion to reduce to the minimum danger of distortion of the member due to excessive changes in temperature while passing through a kiln chamber.

Another object of the invention is to provide an improved material supporting or holding member adapted to be carried by a kiln truck and comprising a base, portions of which extend laterally to either side of the truck frame and a plurality of spaced integral webs which rest on the truck frame and support and reinforce the base from side edge to side edge.

A further object of the invention is to provide a kiln truck having a main body portion adapted to project into and move through a longitudinally extending space formed in the bottom of a kiln chamber and support in the latter a material holding member which extends laterally beyond the side walls of the space and in spaced relation to the side and bottom walls of the chamber to allow circulation of the air, radiant heat or gases of combustion below such member, as the truck moves relative to the several zones in the kiln chamber.

A still further object of the invention is to provide an improved material holding member comprising a base and spaced transversely extending supporting webs serving to per-

mit the heating and cooling mediums to pass or circulate under the base.

Other objects of the invention will be apparent to those skilled in the art to which my invention relates from the following description taken in connection with the accompanying drawings, wherein

Fig. 1 is a side view of a kiln truck embodying my invention.

Fig. 2 is an elevation (enlarged) of the material supporting member.

Fig. 3 is an end elevation of the member.

Fig. 4 is a plan view of the member.

Fig. 5 is a section on the line 5—5 of Fig. 2.

Fig. 6 is a transverse section of the truck on the line 6—6 of Fig. 1 and also a transverse section of a kiln showing the relation of the truck and the material supporting member to the kiln while passing therethrough.

In the drawings, 1 indicates as an entirety a kiln of the continuous type having a longitudinally extending chamber 2 consisting of contiguous zones through which the material or ware to be treated is passed. 75 3 indicates a combustion space above the chamber 2. The bottom wall of the chamber 2 is formed centrally and longitudinally from end to end with a passage or space 4, the purpose of which will later appear. 80

The kiln 1 herein shown is preferably constructed similarly to the kiln disclosed and claimed in my copending application filed November 17, 1928, Ser. No. 320,175; I have shown only a portion of the kiln to illustrate 85 one practical application of my invention.

5 indicates as an entirety a truck having suitable wheels 6 which roll on tracks 7, the latter being related to the opening 4 to guide the truck relative thereto. The frame for 90 the truck 5 comprises a sill 8, having at its opposite ends bolsters 9, each rigidly secured to an inverted, substantially U-shaped member 10, the legs of which have aligned journals, 11 for an axle 12. The sill 8 consists of 95 a long, relatively narrow casting shaped to form a longitudinal recess or seat 13, the walls of which reinforce the casting to withstand thrusts incident to the force imparted endwise through these sills to move the load- 100

ed trucks on their tracks from end to end of the kiln 1. 14 indicates a body member seated in the recess 13 and preferably co-extensive therewith. The body member 14 extends upwardly through the space 4 and carries on its upper surface one or more (preferably three) holding members 15 for the material or ware to be treated in the kiln chamber 2. The body member 14 is formed from suitable refractory material to withstand high temperatures in the kiln. The width or thickness of the member may be determined by the width of the space 4 with suitable clearances to avoid contact with the sides of the space. The member 14 may be of any desired height so that its upper surface 14' may lie in any desired plane relative to the bottom wall of the chamber 2, and such surface may be widened laterally, as shown at 14a. 16 indicates a groove disposed centrally and extending longitudinally of the surface 14' and arranged to receive a complementary rib 17 provided on the member 15, as will later be set forth. The groove 16 and rib 17 may be reversed. The purpose of these elements is to interlock each member 15 to the body member 14 so that (1) the former will have a predetermined relation to the latter and hence be properly spaced within the chamber 2 and (2) the member will be held against sliding laterally on the surface 14a of the body member 14.

Each material holding member 15 comprises a base 15a having a plurality of spaced webs 15b, which extend in a direction transversely of the truck 5 or at right angles to its direction of movement. The base 15a is preferably planular and extends laterally beyond the opposite sides of the truck body member 14, so as to be adaptable to a construction of kiln such as shown herein. As shown, the base 15a and each web have substantially equal thickness and their adjacent inner walls 18, 19, are provided with or connected by fillets 20, instead of defining one with another sharp angles which would make casting difficult and permit cracks to result due to slight expansion or shrinkage. By integrally connecting the base and webs as shown, not only is casting of the member facilitated, but, the above referred to difficulties are eliminated. In my construction of holding members, the webs 15b extend transversely to the direction of movement of the material. This permits the radiant heat or gases, as the case may be or any other circulating medium to pass below the base from one side to the other in either direction. Due to the fact that the webs 15b extend transversely, the base 15a is longer in this direction than in the direction of movement of the truck, which permits me to mount a plurality of members 15, side by side, on each truck, their total width being approximately equal to the length of the truck so that

the end members 15 on one truck will abut the end members on the adjoining trucks during movement of the latter through the kiln. The body member 14 being relatively narrow, the webs 15b have seating portions 15b', preferably of a length equal to the width of the surface 14a, and from the opposite ends of these seating portions, the opposite end edges 15c of the webs extend upwardly at an inclination (see Fig. 2) to or near the free end walls of the base 15a, so that the latter is supported and reinforced from side edge to side edge and its cantilever or lateral portions are adequately supported. By inclining the web ends downwardly and inwardly as shown, obstruction to the circulation of the heat, gases or other medium into the spaces between webs is reduced and a larger portion of the base bottom is directly exposed to these mediums. As will be understood the interlocking ribs 17 are provided centrally of the seating portions 15b'.

The upper surface of the base 15a is preferably provided with up-standing bosses 21, preferably in staggered relation. By providing bosses, the ware laid thereon will be in spaced relation to the surface of the base so that operatives may readily remove the ware. Where tile or slabs are passed through the kiln, this space makes it possible to readily engage them with the hands or suitable implements.

In casting the holding members 15, I prefer to use clay or a clay mixture that has a relatively low co-efficient of expansion to reduce to a minimum danger of distortion due to excessively high temperatures and differences in temperature such as are provided in the kiln chamber.

To those skilled in the art to which my invention relates many changes in construction and widely differing embodiments and applications of the invention will suggest themselves without departing from the spirit and scope thereof. My disclosures and the description herein are purely illustrative and are not intended to be in any sense limiting.

What I claim is:

1. A kiln truck comprising a wheel mounted frame, a vertically disposed body member forming a support, and a material holding member consisting of a base extending laterally to either side of said body member and spaced webs extending from side edge to side edge of said holding member and resting on said body member.
2. A kiln truck comprising a wheel mounted frame, a vertically disposed body member forming a support, and a material holding member consisting of a base extending laterally to either side of said body member and spaced webs extending from side edge to side edge of said holding member and resting on said body member, said webs extend-

ing transversely to the direction of travel of the truck.

3. A kiln truck comprising a wheel mounted frame, a vertically disposed body member forming a support, a material holding member consisting of a base extending laterally to either side of said body member and spaced webs extending from side edge to side edge of said holding member and resting on said body member, and interlocking elements between one of said webs and said body member.

4. A kiln truck comprising a wheel mounted frame, a vertically disposed, relatively narrow refractory member forming a support, and a material holding refractory member consisting of a base extending laterally to either side of said body member and spaced webs extending from side edge to side edge of said holding member and resting on said body member.

5. A holding member for conveying material through a kiln chamber and formed from refractory material, said member comprising a base and spaced integral supporting and reinforcing webs having intermediate seating portions and upwardly inclined ends to support the lateral sides of the base.

6. A holding member for conveying material through a kiln chamber and formed from refractory material, said member comprising a base and spaced integral supporting and reinforcing webs having intermediate seating portions and upwardly inclined ends to support the lateral sides of the base, and interlocking elements on said seating portions.

7. A holding member for conveying material through a kiln chamber and formed from refractory material and comprising a base and spaced integral supporting and reinforcing webs, said base and webs being of substantially equal thicknesses.

8. A holding member for conveying material through a kiln chamber and formed from refractory material and comprising a base and spaced integral supporting and reinforcing webs, said base and webs being of substantially equal thicknesses and the webs having intermediate seating portions and upwardly inclined ends to support the lateral sides of the base.

9. A holding member for conveying material through a kiln chamber and formed from refractory material and comprising a base and spaced integral supporting and reinforcing webs, the adjacent walls between the bottom of the base and sides of the webs being joined with fillets.

60 In testimony whereof, I affix my signature.

HARRY M. ROBERTSON.
